UNITED STATES PATENT OFFICE.

NATHAN F. HOPKINS, OF ROCKLAND, MASSACHUSETTS, ASSIGNOR TO UNITED SHOE MACHINERY CORPORATION, OF PATERSON, NEW JERSEY, A CORPORATION OF NEW JERSEY.

LOCK-STITCH SEWING MACHINE.

Application filed January 10, 1922. Serial No. 528,313.

The invention relates to lock stitch sewing machines such as are used in the manufacture of shoes for sewing the outsole to the welt of a welt shoe.

5 It has been found desirable in machines of this class to actuate certain parts, such as the needle, awl, and take-up by constantly rotating cranks owing to the increased speed which may thus be secured. This manner 10 of actuating the take-up, particularly in connection with a crank actuated needle, renders it difficult to accurately control the delivery of thread to the various thread handling devices of the stitch forming mechanism.

15 An auxiliary take-up has heretofore been utilized to cooperate with the crank operated take-up in controlling the thread but has not proved wholly satisfactory due to complication of parts resulting 20 in wear and breakage and also due to the failure under some conditions and when operating with certain classes of thread to maintain the proper tension on the thread while being manipulated by the stitch forming 25 devices, particularly the loop spreader and the hook or shuttle which carries the loop over the bobbin case for the locking thread.

It is accordingly the object of the present 30 invention to provide for the accurate control of the thread when operated on by a crank actuated take-up and to that end it comprises the features of construction and combination of parts hereinafter described 35 and set forth in the claims.

In the accompanying drawings the preferred form of the invention is shown applied to an outsole stitching machine having the same general construction and mode 40 of operation as the machine shown and described in Patent No. 1,169,909, dated February 1, 1916. Fig. 1 is a sectional elevation showing so much of the machine as is necessary to illustrate the application of the 45 present invention thereto, Fig. 2 is a partial front elevation, Fig. 3 is a section on line 3—3, Fig. 1, and Fig. 4 is a detail of the auxiliary take-up.

The machine shown is provided with a 50 work support 2, a presser foot 4, a crank actuated curved hook needle 6, a crank actuated awl 8, a looper 10, a thread finger 12, a loop spreader 14 a continuously rotating loop taking hook 16 and a thread pull-

off 18 and thread measurer 20, all of which 55 are constructed and actuated as in the machine of said patent. The machine is also provided with rear and front thread locks 22 and 24 carried on opposite ends of a lever 26. The lever is secured to a rock shaft 60 28 which is rocked to alternately engage the locks with the thread through a second rock shaft 30 connected therewith by gear segments 32 and actuated by a cam 34 and cam lever 36 through a yielding connection partially indicated at 38.

The means for taking up the needle loop to set the stitch and for controlling the thread supplied to the thread finger, looper, 70 needle, loop spreader and rotary hook while these thread handling devices are acting to pass a loop of needle thread through the work and over the bobbin case comprises a crank operated take-up 40, an unyielding positively actuated auxiliary take-up 42 and 75 a tension 44 between the take-up and the work through which the stitch forming devices draw the thread given up by the take-ups or either of them. The tension acts on the thread comparatively close to the work 80 and before the thread reaches the looper so that any slack thread which may occur in the system due to the use of the crank motions for actuating the take-up or for actuating the take-up and the needle does not affect 85 the thread which is being operated on by the thread handling devices of the stitch forming mechanism. The thread acted on by these devices is drawn by them through the tension as required and sufficient tension 90 is therefore maintained on the thread to cause it to be raised by the loop spreader and passed about the bobbin case by the rotary hook in a certain and reliable manner without danger of the breakage which frequently 95 occurred in prior constructions due to the pulling of slack thread through the work by these devices and the consequent jamming of the thread between the hook and race-way. The constant tension on the thread 100 also secures a more uniform formation of the stitch and location of the lock than has heretofore been practical with constructions in which the needle loop is taken up and the stitch set by a crank operated take-up. The 105 provision of the tension between the take-up and stitch forming devices also permits the use of a rigid or unyielding auxiliary take-

up to cooperate with the crank actuated take-up with a resulting increase in the strength and durability of the auxiliary take-up mechanism.

5 In the construction shown the take-up 40 is mounted on one arm of a lever 46 and is actuated from a continuously rotating crank 48 through a bell crank lever 50, one arm of which is connected by a link 52 to the 10 take-up lever, and the other arm of which is connected by a link 54 with the crank. The auxiliary take-up 42 is mounted directly on a rigid arm 56 secured to a rock shaft 58. The rock shaft is provided with an arm 60 15 which is connected to one link of a toggle 62, the center joint of which is connected by a link 64 with a cam operated lever 66. The tension 44 is arranged close to the under side of the work and as shown comprises 20 two disks mounted on the pivot stud 68 for the thread finger 12 and forced together by the spring 70.

The thread leads from the wax pot 72, about a tension wheel 74, about a roll 76 25 with which the rear thread lock 22 cooperates, through the guides of the thread measurer 20, through a guide 78 on the plate which cooperates with the front thread lock 24, over the take-ups 42 and 40, and then 30 between the disks of the tension 44 to the thread handling devices of the stitch forming mechanism. During the action of the thread finger, looper, needle, loop spreader and rotary hook the crank operated take-up 35 40 and the rigidly mounted take-up 44 are actuated to give up thread to each of these devices and to keep the thread in the system as nearly taut as practicable. This thread is drawn through the tension 44 as required 40 by each of the thread engaging devices so that they are always acting upon a taut thread, thus insuring their uniform and reliable operation throughout the sewing.

While it is preferred to employ the specific 45 construction and arrangement of parts in embodying the invention in the machine of the patent above referred to it will be understood that this construction and arrangement is not essential to the broader features 50 of the invention and may be varied or modified as found desirable or best suited to the construction and mode of operation of

the machine in which they are to be embodied.

What is claimed is:

55 1. A lock stitch sewing machine having, in combination, stitch forming mechanism including a hook needle, a looper and a loop taker, a take-up, a continuously rotating crank for actuating the take-up, an auxiliary take-up, and a tension between the take-up and stitch forming mechanism through which the stitch forming mechanism draws the thread given up by the take-up.

60 2. A lock stitch sewing machine having, in combination, stitch forming mechanism including a hook needle, a looper and a loop taker, a take-up, a continuously rotating crank for actuating the take-up, a rigid 65 positively actuated auxiliary take-up, and a tension between the take-up and stitch forming mechanism through which the stitch forming mechanism draws the thread given up by the take-ups.

70 3. A lock stitch sewing machine having 75 in combination, stitch forming mechanism including a hook needle, a looper and a continuously rotating loop taker, a take-up, continuously rotating cranks for actuating the needle and take-up, a rigid positively actuated auxiliary take-up and a tension close 80 to the work through which the stitch forming mechanism draws the thread given up by the take-ups.

75 4. A lock stitch sewing machine having, 85 in combination, stitch forming mechanism including a hook needle, a looper, a loop spreader and a loop taker, an oscillating take-up a continuously rotating crank for actuating the take-up, and a tension through 90 which the thread passes from the take-up to the looper.

5. A lock stitch sewing machine having, 95 in combination, stitch forming mechanism including a hook needle, a looper and a continuously rotating loop taker, a take-up, continuously rotating cranks for actuating the needle and take-up, and a tension between the take-up and stitch forming mechanism through 100 which the stitch forming mechanism draws the thread given up by the take-up.

NATHAN F. HOPKINS.
